(57) CLAIM

The ornamental design for a dimpled hard material surface for golf travel cases as shown and described.

DESCRIPTION

FIG. 1 is a top view in perspective of a swatch or small sample of a dimpled hard material surface for golf travel cases in accordance with my new design.

FIG. 2 is a bottom view in perspective of the swatch of dimpled hard material surface for golf travel cases depicted in FIG. 1.

FIG. 3 is a top view in plan of the swatch of dimpled hard material surface for golf travel cases depicted in FIG. 1.

FIG. 4 is a bottom view in plan of the swatch of dimpled hard material surface for golf travel cases depicted in FIG. 1.

FIG. 5 is a front view in elevation of the swatch of dimpled hard material surface for golf travel cases depicted in FIG. 1.

FIG. 6 is a rear view in elevation of the swatch of dimpled hard material surface for golf travel cases depicted in FIG. 1.

FIG. 7 is a right side view in elevation of the swatch of dimpled hard material surface for golf travel cases depicted in FIG. 1.

FIG. 8 is a left side view in elevation of the swatch of dimpled hard material surface for golf travel cases depicted in FIG. 1; and,

FIG. 9 is a perspective view of an example of a golf travel bag incorporating the dimpled hard material surface for golf travel cases depicted in FIGS. 1-8.

The design comprises a dimpled hard material surfaces of golf travel cases. The broken lines in FIGS. 1-8 depict the claim boundary and form no part of the claimed design. The broken lines in FIG. 9 showing a golf travel bag depict environment and form no part of the claimed design.
